MARIO RUSSO, OF NEW ROCHELLE, NEW YORK

DESIGN FOR A LAMP SHADE

Application filed July 20, 1931. Serial No. 40,606. Term of patent 3½ years.

To all whom it may concern:

Be it known that I, MARIO RUSSO, a citizen of the United States, residing at New Rochelle, county of Westchester and State of New York, have invented a new, original, and ornamental Design for a Lamp Shade or Similar Article, of which the following is a specification, reference being had to the accompanying drawings, forming part thereof.

Figure 1 is a front elevation of a lamp shade, showing a complete panel of my new design, said panels being repeated according to the outer circumference of the lamp shade,

said design consisting of a silk body with two different shades of mica configuration on the top thereof; the upper mica being shaded with vertical lines to denote a dark color, and the inner mica being shaded with horizontal lines to denote lightness of color; and

Figure 2 is a sectional view taken on line 2—2 of Figure 1 to more particularly set forth the combination of the silk body and the mica covering.

I claim:—

The ornamental design for a lamp shade or similar article as shown and described.

MARIO RUSSO.
